UNITED STATES PATENT OFFICE.

GEORGE H. HESS, OF LA GRANGE PARK, ILLINOIS.

HOT-AIR FURNACE.

1,236,171.

Specification of Letters Patent.

Patented Aug. 7, 1917.

Application filed February 10, 1917. Serial No. 147,763.

To all whom it may concern:

Be it known that I, GEORGE H. Hess, a citizen of the United States, residing at La Grange Park, in the county of Cook and State of Illinois, have invented new and useful Improvements in Hot-Air Furnaces, of which the following is a specification.

My primary objects are to provide improvements in furnaces to the end that the distribution of the hot air discharged throughout the parts of a building from the furnace may be effected in the desired degree.

I have devised my improvements for incorporation more particularly in the type of furnace commonly known as the pipeless furnace wherein the air heated by the furnace and to be supplied to the rooms, discharges upwardly through a single opening 20 in the top of the furnace, through a relatively large register preferably placed in the central portion of the building, the air introduced into the furnace for heating, and discharged therefrom as stated, usually being drawn from the rooms to be heated and conducted into the furnace through openings in the floor surrounding the portion of the register through which the heated air is discharged from the furnace into the rooms. 25 This type of furnace presents a number of advantages over the other common forms, especially where the rooms to be heated are arranged in compact relation and the arrangement is conducive to a free circulation 30 of the air through the rooms and into and out of the furnace. The usual plan of house, however, is such that there is usually a room, such as a bath-room, which is required, at least part of the time, to be heated to a greater temperature than is possible where the heat supplied thereto discharges 35 from a single register located centrally of the rooms, and it is my more particular object to provide improvements in furnaces to 40 the end that the salient features of a so-called pipeless furnace may be availed of and provision be made for furnishing a sufficient amount of additional heat to a room or rooms not sufficiently heated from the main 45 register of the furnace.

Referring to the accompanying drawings, Figure 1 is a view in front elevation of a furnace possessing the general characteristics of one of the so-called pipeless type 50 and equipped with my improvements, certain portions of the furnace being shown in

sectional elevation. Fig. 2 is a section taken at the line 2—2 on Fig. 1 and viewed in the direction of the arrow; and Fig. 3, a section taken at the line 3—3 on Fig. 1 and viewed in the direction of the arrow. The radiator of the furnace, which is of common construction and is provided with the smoke-flue 4, is represented at 5. Any suitable form of radiator for heating the air, supplied to the 55 furnace as hereinafter described, may be employed, and thus detailed description thereof is unnecessary, the radiator in the construction shown being supported upon beams 6. Surrounding the radiator and arranged in spaced relation thereto, preferably as represented, is a jacket 7 which may be of sheet-iron, or any other suitable material, and which in the construction shown is of rectangular shape in cross-section, this also 60 being the shape of the radiator and the inner jacket hereinafter referred to, though this is not essential to the carrying out of the invention. The upper end of the jacket 7 is of reduced cross-sectional area, as represented at 8, the side and rear walls of this jacket inclining upwardly and toward the center of the furnace, as represented at 9 and 10, respectively. The upper end of the jacket 7 is open and communicates with a 65 register 11 positioned in the opening 12 in the floor 13, this register being located as in the case of the usual pipeless furnace installations. Between the walls of the radiator 5 and the jacket 7 is an inner jacket 14 70 of the same general shape as the jacket 7, and preferably spaced from the radiator and jacket 7, as represented, to afford the inner air-ascending space 15 between the jacket 14 and the radiator and the outer air-descend- 75 ing space 16 between the jackets 7 and 14, these two spaces preferably extending almost completely around the radiator as illustrated more particularly in Fig. 3. The bottom of the jacket 14, which is open as indicated, reaches short of the bottom of the furnace whereby the spaces 15 and 16 are in communication with each other at their lower ends as represented, the upper end of the jacket 14 being open and opening 80 into the central portion of the register 11. 85 The space 15 is divided into two upright conduits 17 and 18 by partition means comprising the partition sections 19 arranged in the space 15 at opposite sides of the radiator 5 and a partition section 20 which is connected with the upper ends of the sec- 90 95 100 105 110

tions 19 and extends across the top of the radiator, the partition section 20 containing an opening 21 controlled by a hinged damper 22 having a sliding operating-rod 23 the outer end of which extends through an opening in the front of the furnace adapting the damper to be rocked into and out of a position in which it closes the opening 21. A hot air conducting pipe 24, and which 10 would lead to a register in a room desired to be heated to a greater temperature than is practically possible through the means of the register 11, such as a bath-room, extends through an opening 25 in the wall 10 of 15 the outer jacket 7 and through an opening 26 in the inner jacket 14 and opens into the air-ascending compartment 17.

In the operation of the furnace the air within the separate compartments 17 and 20 18 is heated by the radiator 5 and thus rises through these compartments, discharging through the central portion of the radiator 11 from the compartment 18 and through the pipe 24 from the compartment 17 when the 25 damper 22 is closed, the air being supplied to the furnace, in the particular construction illustrated, from the marginal portions of the radiator in communication with the space 16, the air following the course of 30 the arrows indicated in Fig. 1.

By the arrangement shown the main body of heated air is caused to discharge through the central register 11, and a body of air of relatively less volume is caused to discharge into the pipe 24, this being rendered possible as the air-heating surfaces of the radiator act upon the air in the separate compartments 17 and 18, and thus the air is propelled through the separate outlets.

40 When it is desired that the discharge of air through the pipe 24 be discontinued, the damper 22 is opened, which establishes communication between the upper ends of the compartments 17 and 18 and permits the air 45 ascending through both of these compartments to discharge through the central portion of the radiator 11.

While I have shown my invention as applied to an air-heating furnace of a particular type, for use in connection with which 50 I have more particularly devised my invention, it will be readily understood that certain features thereof may be utilized in other types of furnaces, it being my intention to 55 claim my invention for use in any type of furnace in which it may be incorporated, and to claim the invention as completely as the prior state of the art will permit.

What I claim as new and desire to secure 60 by Letters Patent is:—

1. In a hot air furnace, the combination of a radiator, a jacket surrounding the radiator and spaced therefrom, an inner jacket between said radiator and said first-named jacket and dividing the space be-

tween said radiator and said first-named jacket into an air-descending space and an inner air-ascending space, said spaces communicating with each other at their lower portions, means extending along the radiator and dividing said air-ascending space into a plurality of flues, said air-descending space between said jackets opening at its upper end into a register and one of said air-ascending flues opening through said 75 register, means communicating with the other of said flues for discharge of the heated air therefrom at a different point, and means whereby the heated air ascending through said last-referred-to flue may be 80 caused to pass through the register or through the said last-mentioned discharge.

2. In a hot air furnace, the combination of a radiator, a jacket surrounding the radiator and spaced therefrom, an inner jacket between said radiator and said first-named jacket and dividing the space between said radiator and said first-named jacket into an air-descending space and an inner air-ascending space, said spaces communicating with each other at their lower portions, means extending along the radiator and dividing said air-ascending space into a plurality of flues, said air-descending space between said jackets opening at its 90 upper end into a register and one of said flues opening through the central portion of said register, means communicating with the other of said flues for discharge of the heated air therefrom at a different point, and means whereby the air in said last-referred-to flue may be caused to pass through the register, or be discharged at said different point.

3. In a hot air furnace, the combination of a radiator, a jacket surrounding the radiator and spaced therefrom, an inner jacket between said radiator and said first-named jacket and dividing the space between said radiator and said first-named jacket into an outer air-descending space and an inner air-ascending space, said spaces communicating with each other at their lower ends, means extending along the radiator and dividing said air-ascending space into a plurality of flues, said air-descending space between said jackets surrounding one of the flues and opening at its upper end through a register, and said last-referred-to flue opening through the central portion of said register, means communicating with the other of said flues for discharge of the heated air therefrom at a different point, and means whereby the heated air ascending through said last-referred-to flue may be caused to pass through the register or to be discharged at said different point.

4. In a hot air furnace, the combination of a radiator, a jacket surrounding the radiator and spaced therefrom, an inner jacket be-

5 tween said radiator and said first-named jacket and dividing the space between said radiator and said first-named jacket into an air-descending space and an inner air-ascending space, said spaces communicating with each other at their lower portions, means extending along the radiator at opposite sides thereof and dividing said air-ascending space into a plurality of flues, said air-descending space between said jackets opening at its upper end into a register and one of said flues opening through the central portion of said register, means communicating with the other of said flues for discharge of 10 the heated air therefrom at a different point, and means whereby the heated air ascending through said last-referred-to flue may be caused to pass through the register or through the said last-mentioned discharge.

15 20 5. In a hot air furnace, the combination of a radiator, a jacket surrounding the radiator and spaced therefrom, an inner jacket between said radiator and said first-named jacket and dividing the space between said 25 radiator and said first-named jacket into an air-descending space and an inner air-ascending space, said spaces communicating with each other at their lower portions, means extending along the radiator at opposite sides thereof and dividing said air-ascending space into a plurality of flues, said air-descending space between said jackets opening at its upper end into a register and one of said flues opening through the central portion of said register, and means communicating with the other of said flues for discharge of 30 the heated air therefrom at a different point, means whereby the heated air ascending through said last-referred-to flue may be caused to 35 discharge through the central portion of said register, and means whereby the heated air ascending through said last-referred-to flue may be caused to pass through the register or through the said last-mentioned discharge.

40 45

6. In a hot air furnace, the combination of a radiator, a jacket surrounding the radiator and spaced therefrom, an inner jacket between said radiator and said first-named jacket and dividing the space between said radiator and said first-named jacket into an outer air-descending space and an inner air-ascending space, said spaces communicating

with each other at their lower portions, the upper ends of said jackets being of less cross-sectional area than the lower portions thereof, a register in communication with the upper constricted end of said outer jacket and in communication at its central portion with the upper constricted end of 55
said inner jacket, partition means extending along opposite sides of said radiator and dividing said air-ascending space into a plurality of flues, one of said flues communicating with the central portion of said register, 60
the upper end of said partition means being located at one side of said constricted portion of said inner jacket and terminating at their upper end adjacent the portion of 65
said wall connecting the constricted portion of said inner jacket with the other portion thereof, and the pipe communicating with the other of said flues. 70

7. In a hot air furnace, the combination of
a radiator, a jacket surrounding the radiator 75
and spaced therefrom, an inner jacket be-
tween said radiator and said first-named
jacket and dividing the space between said
radiator and said first-named jacket into an
outer air-descending space and an inner air- 80
ascending space, said spaces communicating
with each other at their lower portions, the
upper ends of said jackets being of less
cross-sectional area than the lower portions
thereof, a register in communication with 85
the upper constricted end of said outer
jacket and in communication at its central
portion with the upper constricted end of
said inner jacket, partition means extending
along opposite sides of said radiator and 90
dividing said air-ascending space into a plu-
rality of flues, one of said flues communi-
cating with the central portion of said reg-
ister, the upper end of said partition means
being located to one side of said constricted 95
portion of said inner jacket and terminating
at their upper end adjacent the portion of
said wall connecting the constricted portion
of said inner jacket with the other portion
thereof, and the pipe communicating with 100
the other of said flues, said partition means
containing an opening controlled by a valve,
whereby said flues may be caused to com-
municate with each other or be out of com-
munication, at will, for the purpose set forth. 105
